US0D1041660S

(12) **United States Design Patent** (10) Patent No.: **US D1,041,660 S**
(45) Date of Patent: ** Sep. 10, 2024

(54) **WRIST ELECTRONIC SPHYGMOMANOMETER**

(71) Applicant: **Dongguan Kangweile Electronic Technology Co., Ltd.**, Dongguan (CN)

(72) Inventor: **Zhixin Gao**, Dongguan (CN)

(73) Assignee: **Dongguan Kangweile Electronic Technology Co., Ltd.**, Dongguan (CN)

(**) Term: **15 Years**

(21) Appl. No.: **29/879,638**

(22) Filed: **Jul. 11, 2023**

(51) LOC (14) Cl. **24-02**

(52) U.S. Cl.

USPC **D24/165**

(58) **Field of Classification Search**

USPC D24/107, 164-169, 185-187, 200, 216; D10/98; D14/344

CPC A61B 5/0404; A61B 5/021; A61B 5/024; A61B 5/02438; A61B 5/681; A61B 5/0402; A61B 2560/0462

(57) **CLAIM**

The ornamental design for a wrist electronic sphygmomanometer, as shown and described.

DESCRIPTION

FIG. 1 is a front, right and top perspective view of a wrist electronic sphygmomanometer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings illustrate portions of the wrist electronic sphygmomanometer that form no part of the claimed design.

1 Claim, 8 Drawing Sheets
